CASE FOR EGGS AND LIKE COMMODITIES

Application filed May 14, 1928. Serial No. 277,583.

This invention relates to a case for the accommodation of eggs or like commodities. It is a primary object of my invention to devise for the purpose mentioned a case which will be inexpensive, which may be set up in completed form with small labor and expense, which may be nested with others for shipment so as to occupy a minimum of space, which is composed of a non-absorbent and 10 non-odorous material, which is provided with means for ventilating the interior, and which, together with its contents, may be dipped in a bath, or otherwise subjected to a moistening or aerating treatment, for the 15 processing of the eggs or other contained commodities.

An egg case answering to the above requirements may be variously produced, as, for example, according to the suggestive 20 exemplifications thereof which are illustrated in the accompanying drawings in the manner following:

Figure 1 is a view in elevation of one side of the case;

Fig. 2 is a fragmentary elevation of the upper portion of one end of the case;

Figs. 3 and 4 are transverse sections through the case taken, respectively, on lines 3—3 and 4—4 of Fig. 1;

Fig. 5 is a detail in horizontal section taken on line 5—5 of Fig. 4;

Fig. 6 is a sectional detail taken on line 6—6 of Fig. 1;

Fig. 7 is an enlarged detail in section taken 35 on line 7—7 of Fig. 2;

Fig. 8 is an enlarged detail in section taken on line 8—8 of Fig. 2;

Fig. 9 is an enlarged detail in section taken on line 9—9 of Fig. 4;

Fig. 10 is an end elevation showing in nested relation a number of case sides and bottoms as the same appear ready for shipment and prior to complete assembly; and

Fig. 11, which is a view in perspective, 45 shows a case of slightly modified construction.

The present case may desirably be formed of sheet metal with a bottom 12 integrally joined to sides 13 which initially upstand 50 in a slightly divergent relation, as suggested

in Fig. 10. The metal blank may also be provided at its opposite ends with extensions adapted when bent up to form end walls 14 which connect with the side walls so as to provide a four-sided enclosure. Over the 55 open top of the case so constructed is arranged a lid 15.

The up-bending of the two sides from the bottom may be preformed. The line of bend between the two ends and the bottom may 60 conveniently be determined by a scoring of the metal sheet, whereby to assure a correct bending of the ends when the case is set up for use. A convenient lock between the ends and the sides is suggested in Fig. 6, wherein 65 it will be noted that the sides extend slightly past the upturned ends, which latter are provided with outwardly extended ears 16 adapted to pass through slits 17 formed through the sides adjacent the ends thereof. 70 These ears may then be bent around and clinched in place, as shown.

The lid is provided by preference with a depending flange 18 which overlies the adjacent portions of the case sides and ends. 75 Any suitable means may be provided for locking the lid in place, and for this purpose I may use depending ears 19 adapted to pass behind straps 20 which are offset outwardly from the case ends, the ears then being bent 80 around at 21 to clinch the straps upon the outer sides thereof (see Fig. 7). In some such manner as this the lid may be secured detachably and tightly to the case.

It is usual in a container of the character in question to provide a central partition, and for this purpose I have suggested, as shown in Fig. 5, a plate 22 which is extended centrally between the two case sides. The bottom edge of this plate may be braced on 85 opposite sides by ears 23 which are upstruck from the case bottom 12 and an anchorage along the sides of the partition may be provided by striking in from the case sides ears 24 which are slotted to receive therethrough 90 tongues 25 extending from the proximate vertical edges of the partition plate. These tongues, as best illustrated in Fig. 5, may 95 also be bent around and clinched upon the ears 24 to effect a tight connection therewith. 100

Referring now to Figs. 2 and 8, I have shown for the two ends of the lid a special construction of depending flange. The flange portion 26 between the two ears 19 is outwardly inclined and then bent inwardly at 27 and upwardly again at 28 providing a horizontal gripping surface by which the case may conveniently be handled. Some such means as this is non-protruding and at 10 the same time facilitates lifting or carrying of the case, as required.

For the orderly accommodation of eggs in a case of the kind described, I provide a cellular structure consisting of fillers having a 15 plurality of intersecting walls *a* and *b*. The several fillers are in superposed relation with intervening flats or separator sheets *c*. In this manner I provide a plurality of individual cells or pockets, each adapted for the 20 reception of a single egg or other commodity. The spacing of the walls composing these cells is determined according to the size of the intended contents. For a case having standard dimensions, it is customary to superpose five fillers each having six pockets 25 extending both ways in horizontal rows, making a total capacity of three dozen for each filler. A case which is divided by a central partition 22 into two main compartments is 30 accordingly adapted to receive in each a stack of fillers arranged as indicated in Fig. 3.

As part of my invention, I so configure the interior surfaces of the sides, ends and bottom of the case as to cooperate with the fillers in cushioning the outermost cells so as to better protect the contents thereof against 35 external shocks. This is accomplished by the provision of inwardly extended means which, in the example shown, may take the form of parallel ridges conveniently produced by corrugating the case walls in the manner now to be explained. The side walls of the case are corrugated, preferably horizontally, so as to provide outbends *d* at points 40 substantially midway of the height of each filler, the inbend points coinciding substantially with the horizontal partitions *c*. The bottom of the case may likewise be corrugated from end to end with the outbends *e* at 45 points substantially midway of each row of cells. The end walls which are formed as extensions of the bottom are likewise corrugated, but in a vertical direction, the outbends occurring in line with the middle point 50 of each row of cells. When the fillers are arranged within the case so formed, the flat or separator sheet *c* adjacent the case bottom is rested upon the inbends thereof (see Fig. 3) to support the lowermost layers of eggs in 55 elevated position. Likewise the outside walls *a* and *b* of the fillers which are disposed adjacent the sides and end walls of the case are maintained slightly separated from the outbends thereof by the projecting ends of these 60 fillers (see Fig. 3), so as to protect the eggs 65

from the direct transmission of any external shock. This is a feature of protection which conduces to greater safety in the handling and shipping of the eggs.

It is desirable also for the same reason to 70 safeguard those eggs which lie adjacent the central partition 22. As indicated in Fig. 5, this may desirably be of zig-zag formation so as to present a series of points *h* which 75 outstand on opposite sides from a line extending centrally through the partition. These outstanding points *h* about align with the filler walls *a* the ends of which are adjacent thereto so as to space therefrom the 80 proximate cells in which eggs or other commodities are contained.

The case of my invention may desirably be provided with a number of ventilating openings 35 in the vertical walls thereof. These 85 may be of any desired size and be variously located. Other openings 36 may also be provided in the case bottom as suggested in Fig. 3. The latter openings are preferably at the ends of the case adjacent the corners formed by the upstanding end walls. These openings 90 besides serving a ventilating purpose will also permit the present case, together with eggs therein, to be dipped into a tank whenever processing is desired. By proceeding in this manner, it is not necessary to remove eggs 95 from the case and then replace them after the processing treatment. This manner of procedure is a great saving in time, labor and expense. The processing fluid will be 100 enabled to pass into the case through the top and through the apertures elsewhere provided, and also to enter into each of the egg containing cells, and thereafter upon removal from the tank to drain through any of the 105 case openings which desirably should be located with this purpose in view. For such dipping operations the material composing the fillers and flats may, if desired, be formed of metal, or be so treated as to be non-absorptive and non-odorous, the same as are the 110 walls of the case when produced from metal. There is a distinct advantage in this construction when processing, sterilizing, bleaching, or other treating is to be performed, inasmuch as only one egg packing operation is 115 required. This results from the fact that the eggs when once introduced into the case may thereafter remain undisturbed during any of such treatments, and also subsequently thereto, as during storing, shipping, or 120 handling.

As suggestive of one modification of this invention reference may be had to Fig. 11 wherein is shown a case of metal having sides 113 joined integrally to a bottom (not shown). The ends 114, however, are separate units and may, if desired, be formed of material other than metal—wood, for example. The sides, ends and bottom may be internally convoluted as in the construction of the remain- 130

ing figures, so as to cooperate in the manner already described with the proximate portion of the fillers. Likewise the central partition 122 may be formed from a board having appropriate convolutions on its opposite faces to maintain the proximate cells in a safely spaced relation. The partition and ends may conveniently be secured in place between the sides by nails or other equivalent fastening devices.

10 I claim:

1. In a case of the kind described, the combination of a bottom and four walls joined thereto, a partition extending between two walls and connected therewith to provide two separated compartments, a plurality of means arranged in rows projecting from opposite faces of the partition, and fillers arranged in the compartments of the case on opposite sides of the partition and comprising cross walls so disposed as to present certain of the ends thereof for engagement with said projecting means.

2. In a case of the kind described, the combination of a bottom and four walls joined thereto and to each other, a partition extending between two of the walls and connected thereto, the partition being formed of a sheet having a horizontal cross section which provides opposite points extended laterally from a plane which passes centrally through the partition.

3. In a case of the kind described, the combination of a bottom having walls joined thereto and to each other, the opposite ends of two of the walls protruding slightly beyond the proximate ends of the remaining walls, a lid covering the case and connected to the walls thereof, and means depending from the lid along the non-protruding walls and extended outwardly therefrom a distance substantially equal to the protrusion of the ends of the remaining walls adapted to furnish a hold by which the case may be handled.

4. In a case of the kind described, the combination of a bottom and walls connected thereto and to each other, a lid covering the case and connected to the walls thereof, and a flange depending outwardly from opposite ends of the lid, then inturned to a point adjacent the proximate wall, then upturned to a point adjacent the upper edge thereof.

5. In a case of the kind described, the combination of a bottom having walls connected thereto and to each other, a lid for covering the case connected to the walls thereof, two of the walls having their opposite ends extended past the ends of the remaining walls, and means depending from the lid along the walls last mentioned and extended outwardly therefrom to provide a hold by which the case may be handled.

6. In a case of the kind described, the combination of a bottom having walls connected

thereto and to each other and formed integrally of a metallic sheet wherein are provided openings occurring both in the walls and bottom for the passage therethrough of a fluid, means removably contained within the case forming a multilayer cellular structure, the walls having spaced elongated parallel portions extending inwardly out of the plane of the intermediate portions to provide abutments for the partitions of the cellular structure to prevent shifting of said means within the case and to provide spaces between the sides of the outermost cells and the walls of the case between the elongated portions.

7. In a case of the kind described, the combination of a bottom having walls connected thereto and to each other, two of the walls having their opposite ends extending past the ends of the remaining walls, and means depending from the top edges of the walls last mentioned and extending outwardly therefrom but within the limit of extension of the walls first mentioned, and adapted to provide a hold by which the case may be handled.

8. In a case of the kind described, the combination of a bottom having walls connected thereto and to each other, and two of the walls having their opposite ends extending past the ends of the remaining walls, and means depending from the top of the walls last mentioned and extending outwardly therefrom within the limits of the extension of the walls first mentioned, said means being then inturned against the last mentioned walls and upturned to a point adjacent the upper edges thereof whereby to provide a hold by which the case may be handled.

9. In a case of the kind described, the combination of a bottom having walls integrally connected thereto and each wall having means for connection to each other, means removably contained within the case forming a multilayer cellular structure, said walls having spaced elongated parallel portions extending inwardly out of the plane of intermediate portions and in alignment with partitions of the cellular structure to prevent shifting of the removable means and to provide spaces between the side of the outermost cells and the walls of the case.

10. In a case adapted to removably receive, brace and cushion a plurality of superimposed cellular structures or fillers, a metallic blank cut and scored to define a substantially rectangular bottom and outwardly and upwardly extending side and end portions, said side and end portions having means for interlocking engagement when the sides are brought into abutting relation with the side edges of the end portions, and said side, end and bottom portions having uniformly spaced inwardly protruding ribs extending from edge to edge of said portions, said ribs being a distance apart equal to the width and height of

the cells of the removable cellular structure,
whereby the ribs will align with partitions
between superimposed filler layers to brace
same against shifting movement and to pro-
vide cushion spaces between the sides of the
outermost cells and the walls of the case be-
tween the ribs.

5 In testimony whereof, I have hereunto set
my hand this 11th day of April, 1928.
